(57) **CLAIM**

We claim the ornamental design for a rail shuttle fall arrester, as shown and described.

DESCRIPTION

FIG. 1 is a first perspective view of a rail shuttle fall arrester showing our new design;

FIG. 2 is a second perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is another perspective view thereof, shown in use with a rail.

The broken lines in the drawings depict portions of the rail shuttle fall arrester that form no part of the claimed design. The dash-dot-dash broken lines depict boundaries of the claim and form no part thereof.

Additional broken lines in FIG. 9 depict environmental subject matter that forms no part of the claimed design.
